FEED TROUGH FOR GRADING MACHINES

Otto Fesefeldt, Elmshorn, Germany, assignor to
 Kommandit-Gesellschaft in Firma Peter Kolln,
 Elmshorn, Germany

Application December 2, 1938, Serial No. 243,645
 In Germany June 20, 1938

2 Claims. (Cl. 209—497)

This invention relates to a feed trough for grading machines, in which the preliminarily treated individual grains pass from the trough into chambers of a sorting table carrying out a 5 rocking motion.

In the known types of grading machines the specifically lightest, or unhusked, grains which possess also the greatest elasticity jump farthest, due to the rocking motion of the sorting table, 10 and collect toward the ends of the trough, whereby uniform distribution of the material to the chambers is prevented. Furthermore, as the known troughs have a perfectly smooth bottom, the material contained within them is thoroughly shaken during the motion of the table.

According to the invention, these drawbacks are overcome by providing the trough with a stepped insertion which insures continual upward motion of the individual grains at very slight vibration, in consequence whereof separation of the lighter from the heavier grains is prevented in the trough and the grains pass in a 20 perfectly uniform manner into the chambers disposed underneath the trough.

The accompanying drawing illustrates by way of example one form of the invention.

In the drawing

Figure 1 is a vertical longitudinal section of a trough according to the invention on the line I—I, of Fig. 2, and

Fig. 2 is a plan thereof.

One-half of the troughlike box *a* is provided with a stepped path *b*, *b'*, and the other half has a smooth bottom *f*. Both the path *b*, *b'* and the bottom *f* are preferably lined with tin plate to eliminate resistances which could obstruct the travel of the grain. Toward the center of the trough *a* the stepped path *b*, *b'* is limited by saw-like sheets *c* adapted to the steps and capable of being displaced by means of the slots and pins *d* in such manner that they can occupy a higher or lower position in horizontal direction as well as toward each side in an obliquely ascending

manner. The lateral openings *e* of the trough *b*, *b'* serve as outlets for the material which enters through the inlet *g*.

The mode of operation is as follows:

Owing to the shaking motion of the trough *a* secured to a grading machine the grain entering at *g* is distributed over the steps *b*, *b'* toward both sides of the trough *a*. The sawlike sheets *c* limiting the steps *b*, *b'* are then so adjusted that a uniform stream of grain flows over the steps *b*, *b'* up to the outlets *e* disposed to the right and left at the ends of the trough *a*. Being mounted approximately in the center of the grading machine and, owing to the construction thereof, placed in an inclined position, the trough *a* 15 slightly inclines toward the front side, so that during the shaking of the machine in the longitudinal direction of the trough the grain tends to travel on the steps *b*, *b'* along the sawlike sheets *c* and drops over the sawlike prongs of the sheets *c* 20 into the front half *f* of the trough *a* where it collects at the apertured front wall of the trough *a* until it passes through one of the apertures *e* which lead into the chambers of the grading machine.

I claim:

1. A feed trough for sorting apparatus comprising, a trough-like box, means providing a series of steps arranged longitudinally of the box, said box laterally and longitudinally of said steps having a smooth bottom, means for guiding granular material to be sorted onto said steps, saw-like sheet means adapted to the profile of said steps arranged along the steps providing a separating wall between the surface of the steps and the smooth bottom of the box, and the lateral wall of the box adjacent said smooth bottom having apertures providing outlets for the granular material.

2. Apparatus according to claim 1 wherein the sheet means is adjustable with respect to the steps.

OTTO FESEFELDT.
